UNITED STATES PATENT OFFICE

JOHN F. BENTLEY, OF DETROIT, MICHIGAN

FAUCET

Application filed August 12, 1929. Serial No. 385,403.

This invention relates to combination faucets for delivering either hot, cold or warm water through a single nozzle.

The main object of the invention is to provide in a relatively simple, compact and durable form, a device for the purpose above designated.

Another object is to provide a combination hot and cold water faucet, controlled by a single handle, the lateral movement of which operates to open or close the hot and cold water ports in any required degree, and the vertical movement of which operates to deliver the water through the nozzle.

Another object is to provide in a device of the kind described a water channel controlled by a valve assembly comprising a primary and a secondary valve, the secondary valve being adapted to raise or lift slightly in advance of the larger primary valve, whereby the water pressure upon the valve faces is more easily overcome in the operation of the device.

With these and other objects in view, as will appear in the course of these specifications, attention is called to the accompanying drawings, wherein

Figure 1 is an elevation, partly in section and partly in full lines of the entire assembly;

Figure 2 is a horizontal section on the line 2—2 of Figure 1;

Figure 3 is a view similar to Figure 1, but taken on a sight line perpendicular to the sight line of Figure 1;

Figure 4 is a detail in plan of the primary valve;

Figure 5 is a detail in plan of the double acting port valve.

The invention comprises a suitable shell or casing 1 formed with a circular nozzle opening 2 at the bottom surrounded by an annular washer recess 3 for the reception of a suitable packing washer 4. The casing 1 is open at the top side and is formed with laterally disposed hot and cold water ports 5 and 6 which connect with the laterally spaced water leads or pipes 7 and 8 in conventional manner.

The top of the casing 1 is closed by a cover plate 9 which is fastened down by means of

screws 10. The plate 9 is formed with a central, integral sleeve 11 which projects partly below the plate 9. The sleeve 11 is adapted to receive a thimble 12 which is rotatably mounted therein with its open end downward. A cap 14, having the handle lugs 15 at the apex thereof and being formed with a central socket 16 at its under side for the reception of the upper end of the thimble 12, is provided and rotatably mounted upon the cover plate 9, with the socket 16 engaging the thimble 12 as stated. The thimble 12 is then pinned to the cap 14 by means of a pin 17, so that the thimble will rotate as the cap is rotated. A suitable operating handle 18 is pivoted for vertical movement between the lugs 15 by means of the pin 19. The handle 18 is extended rearwardly as shown; and to it is pivotally pinned at 20 for movement in a vertical plane the handle bar 21 which depends at the rear of the casing 1 and is then bent forwardly and formed into a ring 22 disposed immediately under the nozzle opening 2 of the said casing.

A cylindrical nozzle 23 is snugly but slidably journaled through the nozzle opening 2, its lower end being passed freely through the ring 22 of the handle bar 21. The upper end of the nozzle 23 is bridged by a bridge piece 24 which carries the upwardly projecting valve lug 25. The lower mouth of the nozzle opening 2 is tapered or flared as shown at 26 to complementarily engage a tapered or beveled sealing ring 27 which is fixedly mounted upon the lower end of the nozzle 23. This mounting is accomplished by welding or in any other conventional manner. Thus upon the upward sliding movement of the nozzle, the beveled lift ring 27 enters the flared mouth 26 of the nozzle, and serves as a seal against water under pressure working down the outer face of the nozzle from the inside of the casing 1. A circular primary valve 28 formed at its under side with a bore or seat 29 adapted to snugly but freely engage the upper end of the nozzle 23, and having a reduced opening 30 formed through its upper side, is mounted in place over the upper end of the nozzle 23 in manner described. The valve 28 is countersunk

at its upper side around the opening 30 for the reception of a suitable packing washer 31. Diametrically opposed, guide forks 32 extend laterally from the upper side of the valve 28, and slidingly engage vertical guide lugs 33 formed upon the interior of the casing 1 at the lower portion thereof. Similarly, opposed spring seats 34 extend from the valve 28 laterally towards the side walls 10 of the casing 1. Coil springs 35 braced between the cover plate 9 and the said spring seats 34 serve to normally hold the valve 28 down to its seat upon the washer 4. A secondary valve 36 is adapted to seat upon the washer 31 and close the opening 30 through the primary valve 28. A round stem or shank 37 extends from the valve 36 up into the mouth of the thimble 12. A coil spring 38 seated within the thimble 12 normally forces 20 the valve 36 to its seat upon the washer 31. A circular cam 39 having a valve stem opening 40 eccentrically formed therethrough is rigidly affixed at the lower end of the thimble 12 with the opening 40 aligned with the cavity 25 of the thimble. Thus the valve stem 37 may pass freely through the opening 40 up into the thimble. An oval shaped valve ring or yoke 41 is slidingly mounted over the cam 39, and supports at either end a valve 42 adapted to seat against and close the water ports 5 and 6. The arrangement is such that as the cam 39 oscillates or partially rotates under the movement of the connected handle 18, the yoke 41 is projected laterally towards 30 one side or the other of the casing 1, and the assembly is so proportioned that upon such lateral movement either of the ports 5 or 6 will be closed by the valve 42 at that end of the yoke, while the other one of the said ports 40 remains open for the ingress of water into the said casing. Stops 43 are mounted inside the yoke 41 opposite to the valves 42, and a lug 44 upon the periphery of the cam 39 is adapted to impinge against either of these lugs upon 45 the lateral movement of the cam, whereby the said movement of the cam is limited or stopped at the exact point at which either of the valves 42 becomes fully closed against its opposed water port, 5 or 6. Guide lugs 45 are mounted upon the under face of the cover plate 9 in such position that when the plate 9 is mounted in place upon the casing 1, the lugs 45 will stand vertically aligned with the lower lugs 33. The valves 42 are slotted upon 50 their upper and lower edges as shown at 46, whereby they are slidably mounted between the said lugs 33 and 45 as clearly shown in Figure 3.

60 The ring 27 is so positioned upon the lower end of the nozzle 23 that when that nozzle is in its lowermost position the said ring will stand substantially spaced from the flared mouth 26 of the nozzle opening 2. The valve 65 lug 25 falls just a little short of impinging

against the under face of the secondary valve 36 when the latter is closed.

In the operation of the faucet, either hot, cold or warm water may be admitted into the casing 1 by merely turning the handle 18 laterally whereby the ports 5 and 6 are opened or closed in manner hereinbefore set out, and this water is then passed out through the nozzle 23 by depressing the outer end of the handle 18. In this operation the nozzle 23 is raised by or through the ring 22 striking the ring 27, whereupon the valve lug 25 immediately strikes the secondary valve 36 and forces that valve upward, thereby admitting a relatively small flow of water through the nozzle 23 and relieving to that extent the total of the water pressure upon the upper faces of the two valves 28 and 36. The continued upward movement of the nozzle 23 then results in the upper end 70 of the nozzle impinging against the under face of the primary valve 28, whereby that valve is in turn raised and a full flow of water passes through the nozzle 23.

When the water passing through the casing 1 is under great pressure as is apt to be the case where the operator is taking a shower bath, there is danger that some water may be forced down between the inner wall of the nozzle opening 2 and the outer face 90 of the nozzle 23. As a safeguard against this, the flared mouth 26 is provided for the opening 2 to coact with the beveled sealing ring 27, as above stated. It is noted that with the handle 18 in midway position, both valves 42 shall stand partly open, so that warm water will be discharged, and, of course, by varying the relative degree of closure of the valves, the temperature of the water can 95 be regulated to suit.

100 While I have herein described a preferred embodiment of my invention, it is understood that the structural features referred to may be changed in minor details, without departing from the spirit of my invention as defined in the appended claims.

110 I claim:

115 1. A combination water faucet, comprising a suitable casing open at the top and having laterally disposed hot and cold water ports and a lower centrally located nozzle opening, a cover plate for the top of the casing, the same having a central opening adapted to align with the said nozzle opening, a thimble 120 rotatively mounted in the opening of the cover plate, the mouth of the thimble being directed downward, a cap rotatively mounted upon the cover plate and anchored to the said thimble, a handle pivoted for vertical movement upon the said cap, a handle bar pivoted for vertical movement to the rear end of the handle and depending at the rear of the casing, the lower end of the bar being bent forwardly and formed into a ring immediately below the nozzle opening of the 125 130

casing, a nozzle slidably mounted through the said nozzle opening of the casing, the lower end of the nozzle being disposed freely through the said ring of the handle bar, a lift ring secured to the lower end of the nozzle above the said handle ring, a valve lug extended upwardly from the upper end of the said nozzle, a primary valve seated within the casing over the upper end of the 10 said nozzle, the said primary valve having a central reduced opening, a relatively small secondary valve mounted within the casing upon the primary valve and immediately above the said valve lug at the upper end of 15 the nozzle and adapted to be raised thereby upon the upward movement of the nozzle, the said secondary valve having a stem extending into the mouth of the said thimble, a circular cam eccentrically fixed to the lower 20 end of the thimble, the same having an opening therethrough in alignment with the bore of the said thimble and through which bore the said valve stem of the secondary valve is passed, a valve yoke slidably seated over 25 and operable by the said cam, valves upon the yoke adapted to seal either of the said water ports of the casing upon the oscillation of the said cam, means for holding the said primary and secondary valves to their 30 seats, and means at the upper end of the nozzle for opening the said valves.

2. In a device of the kind described, a casing having oppositely disposed hot and cold water ports, a rotatable element extended 35 into the casing between the said ports, a circular cam eccentrically mounted within the casing upon the said rotatable element, a yoke slidably mounted upon the periphery of the said cam, and valves at the opposite 40 sides of the said yoke adapted alternately to seal either of the said water ports of the casing upon the oscillation of the said cam.

In testimony whereof I affix my signature.
JOHN F. BENTLEY.
